UNITED STATES PATENT OFFICE.

CHARLES S. BENTLEY, OF PLATTSBURG, NEW YORK.

FIBER PICTURE AND PROCESS OF MAKING THE SAME.

1,207,841.

Specification of Letters Patent. Patented Dec. 12, 1916.

Application filed February 17, 1916. Serial No. 73,968.

To all whom it may concern:

Be it known that I, CHARLES S. BENTLEY, a citizen of the United States, residing at Plattsburg, in the county of Clinton and 5 State of New York, have invented certain new and useful Improvements in Fiber Pictures and Processes of Making the Same, of which the following is a specification.

My invention relates to the fine arts, and 10 particularly to the production of pictures by novel means dispensing entirely with paint, and yet giving pictures having the soft, mellow appearance and distance effects of oil paintings.

15 My object is to produce pictures by the use of colored fibrous material instead of paint.

Another object is to produce mounts for entomological specimens and the like, with the fibrous material forming the back of the 20 mount, utilized to form a picture, preferably illustrative of the environment and scenery of the natural habitat of the specimen.

Other objects will appear in the subjoined 25 description.

The invention consists in the novel method of employing colored fiber to form a picture, and of the picture thus formed; and also in the utilization of a fiber picture as a backing 30 for a specimen mount, as hereinafter described and claimed, reference being had to the accompanying drawings, in which,

Figure 1 is a plan view illustrating a picture formed of colored fiber. Fig. 2 is a view showing substantially the same picture 35 utilized as the backing of an entomological specimen mount, the clouds being omitted for the sake of clearness. Fig. 3 is a broken section illustrating a fiber picture and the case containing the same; and, Fig. 4 illustrates a slightly modified way of forming a 40 picture.

As is well known, the finest pictures are ordinarily formed with paint of suitable colors and tints properly spread with 45 brushes on canvas or other desired backing; but in the production of my pictures, instead of paint, I employ fragments of fiber of different colors and shades, said fragments being placed in proper relation to each other 50 to produce the desired effects.

In the production of my pictures, I find it

greatly convenient to have at hand, not only a supply of fiber of all the different colors needed, but also graduated shades of each individual color used. The reason of this 55 becomes at once apparent when we consider that while paint of any given color can be mixed with white to tone it down to a lighter shade, or with other colors to variously modify its shade, that colored fiber cannot 60 be mixed into a homogeneous mass with other fiber of different color to give any different shade or color that may be desired.

In order to produce all the different shades of any given color, I have invented a method 65 of coloring fiber, which method forms the subject matter of another application.

Of course I can produce many beautiful effects in fiber pictures and introduce many different shades of color by taking fiber of a 70 given color and spreading it in films of different thicknesses on top of fiber or other backing of different color. But filming the fiber in this way to obtain different shades of a color, is a slower process than my usual 75 method, as referred to above. For instance, suppose I desire a dash of sunlight in a minute portion of a picture; I can obtain the exact effect desired by taking a suitable portion of fiber of the exact shade of the particular color required, and gently superimposing the same in its proper position on the picture; whereas, to produce the same effect by filming the fiber as indicated above, 80 would be much more difficult. 85

In the production of my pictures I can use any and every known kind of fibrous material—cotton, flax, silk-weed, wool, silk, asbestos, etc. These pictures may be produced by bringing the different portions of 90 variously colored fiber into proper relation to each other to form the pictures, and then securing or holding said parts together in any desired manner; but I have found in practice that the clearness and beauty of 95 these pictures is much enhanced by pressing them under glass. The smooth, even surface of the glass brings the visible part of the fiber, forming the pictures, into an even plane, with the portions of the separate 100 fiber which have come into contact with the surface of the glass disposed parallel with

said surface, thereby exposing to view the glossy sides of the visible portions of the various fibers. This serves the double purpose of bringing a great number of fibers into an even plane so that a glance of the eye will catch the reflection of more of them at one time than would otherwise be possible, and also of disposing the individual fibers in a way to present the greatest possible area of reflecting surface to the eye. This pressure of the glass upon the different colored fibers, forcing them into an even plane, thereby effects such a delicate shading of one tone into another, that the illusion of distance and "atmosphere" may be obtained by the use of comparatively few colors. As soon as the glass is pressed into engagement with the fiber, the colors at once take on new life and beauty, and produce pictures much softer and endowed with greater atmospheric effects than either pastels or water colors. In the different figures of the drawings, I have illustrated a convenient way of holding these fiber pictures in engagement with the glass which also forms a cover for the picture. Referring to these figures of the drawings, the numeral 1 indicates a box, having a cover 2, with the top of the cover all removed except the inwardly extending flange 2^a around its margin. Interposed between the top of the box 1 and the flange 2^a, is the glass 3, which in reality forms the top of the cover. In the box is placed the colored fiber 4 which forms the picture. The lid 2 may be suitably secured on the box in any preferred manner. In the case of specimen mounts, when it is desired to have a considerable depth of fiber in order to permit the butterflies or other specimens to become easily embedded in the fiber when the glass is pressed down upon them, I provide somewhat deeper boxes and fill their bottoms with layers of plain fiber 5. Each kind of fiber has its own peculiar qualities, and hence each has its peculiar adaptability for bringing out the different effects desired in these fiber pictures. For instance, in subjects to which a certain style of painting would be applicable dyed sheep's wool when pressed under a plate of glass or other transparent material produces some very interesting brush marks. It counterfeits to a nicety the apparently haphazard yet remarkable style of a Turner or Claude Monet.

The fiber of wool is flat and glossy, and so thin that it has irregular curls and kinks in it. This accounts in part for the above effects. Silk and spider's web, and many other kinds of fiber, are quite different in structure from wool, and so produce correspondingly different effects in a picture. In making these pictures I use whatever kind of fiber is best suited to the particular subject in hand, and in some cases many differ-

ent kinds of fiber are used in the same picture. Of all the different kinds of fiber, cotton is perhaps the cheapest and most abundant, and I have found that by the use of cotton batting properly colored very satisfactory results may be obtained. 70

In certain kinds of pictures, as for instance, landscape pictures, very striking distance effects are produced by using a plurality of transparent plates, one above the other, with portions of colored fiber between the several plates, the different portions of fiber being so arranged as to form a single picture. If it were attempted to form a picture of this kind by substituting properly colored or painted pieces of paper for the portions of colored fiber between the several transparent plates, the edges of each piece of paper would tend to form a more or less distinct outline on the picture, and thus 75 mar the general effect; but such is not the case with the different portions of fiber, since their edges have no well defined outlines, and therefore each portion seems to merge imperceptibly into that which is beneath it, so that the unitary effect produced is complete. In Fig. 4 of the drawings, I have shown a fragmentary view of a picture formed in this way. In this view, the box 1 with its lid 2 is made deeper than in Fig. 3. 95 Within the box are the transparent plates 6, 7, 8, 9, and 10, with the several portions of colored fiber suitably placed between the plates to form the picture desired. These plates may all be of an equal thickness, or their thickness may be varied according to the distance effects desired to be produced. In the drawings the plates are all shown as 100 of different thicknesses.

Having thus described my invention, what I claim as new and desire to protect by Letters Patent, is:—

1. A picture formed of portions of colored fiber placed together in proper relation to each other relatively to their colors to form 110 the picture; and means for holding said portions of colored fiber in the desired relation to each other.

2. The process of forming pictures by placing together portions of variously colored fibrous material in proper relation to each other relatively to their colors to produce the pictures desired. 115

3. The process of forming pictures by placing together portions of variously colored fibrous material in proper relation to each other relatively to their colors to produce the pictures desired, and superimposing upon the surface of the fiber thus arranged a plate of transparent material pressed into 125 engagement with said surface to bring the surface of the picture into an even plane coincident with the under surface of the transparent plate.

4. A specimen mount comprising a 130

fibrous backing; and a holder for said backing, said backing being formed of portions of variously colored fiber placed together in proper relation to each other relatively to their colors to form a picture illustrative of the environment and scenery of the natural habitat of the specimen; said holder having a transparent top adapted to be pressed into

engagement with the colored fiber forming the picture.

In testimony whereof I affix my signature in the presence of two witnesses.

CHARLES S. BENTLEY.
